ATTORNEYS.

UNITED STATES PATENT OFFICE.

HUGO CLAUSSEN, OF BRONX, NEW YORK.

FASTENER FOR HARVESTING-MACHINE CONVEYER BELTS.

Application filed February 13, 1922. Serial No. 536,121.

To all whom it may concern:

Be it known that I, HUGO CLAUSSEN, a citizen of the Republic of Germany, and resident of Bronx, in the county of Bronx 5 and State of New York, have invented certain new and useful Improvements in Fasteners for Harvesting - Machine Conveyer Belts (for which I have filed application in Germany February 17, 1921, No. 784,018), 10 and of which the following is a specification.

Conveyer belts for harvesting machines usually have their ends secured to each other by suitable means such as straps and buckles, 15 one end of the belt being made to overlap the other for the purpose of covering these securing means, thus ensuring a continuous smooth surface of the belt.

Heretofore it has been the practice to tie 20 the overlapping portions together along the side edges by means of strings. This occasions great loss of time and is a very inconvenient method. The strings will often becomes loose causing considerable delay, 25 and frequently the conveyer belt cloth is torn or otherwise damaged.

The principal object of my invention is to provide a fastening means which will overcome the difficulties and inconveniences 30 of the method set forth above for securing together the overlapping portions of a harvesting machine conveyer belt.

Another object of my invention is to provide a fastening means that will hold the 35 overlapping portions together securely without any possibility of displacement. A still further object of my invention is to provide readily adjustable means for joining the ends of conveyer belts at their overlapping portions without puncturing or perforating the conveyer belt.

For the accomplishment of these and such further objects as will hereinafter be apparent to those skilled in the art to which 45 this appertains, the invention consists in the construction, combination and arrangement of parts herein specifically described and illustrated in the accompanying drawings, wherein is shown a preferred embodiment of 50 the invention, but it is to be understood that changes, variations and modifications may be resorted to which fall within the scope of the claims hereunto appended.

In the accompanying drawings, on which similar reference characters indicate corresponding parts:

Fig. 1 is a perspective view of part of a harvesting machine, showing my fastener secured to the conveyer belt;

Fig. 2 is a perspective view of the fastener;

Figs. 3 and 4 are detail views of different forms of my invention.

Referring to the construction in further detail, "a" refers to the frame; "b" is one 65 end of the conveyer belt to which the buckles are fastened, "c" represents the straps fastened to the conveyer belt, "d" is the overlapping end of the conveyer belt.

In Fig. 2 is shown a perspective view of 70 my fastener. The fastener is stamped out of spring sheet metal or other suitable material in U-shaped form, indicated by reference letter "e" in the drawing. A tongue "f" is riveted or otherwise secured to the 75 U-shaped member and thus two superposed clamping spaces "g" and "h" are formed. Two of the fasteners "f" are clamped along the edges on either side of the conveyer belt portion "b", the conveyer belt cloth entering into the space "g" of the fasteners. The overlapping portion of the conveyer belt "d" is then inserted in the space "h" of the fasteners and is held securely in position by the spring clamping effect. The fasteners 80 can be slid along the sides of the overlapping portion "d" until the fastener is flush with the end of said overlapping portions. In the cases of changes in the conveyer belt cloth due to stretching the fasteners can be 85 suitably adjusted, when necessary. The inner surfaces of the fastener may be serrated or roughened so as to obtain a better hold on the conveyer belt cloth.

The fastener shown in Fig. 3 is substantially the same as the fastener of Fig. 2, but contains in addition a projecting pin "i" secured to the middle blade. On the lower surface of the overlapping conveyer belt portion "d" eyelets "k" are provided which 100 are adapted to engage the pins "i" and thus ensure a better hold.

In the modification shown in Fig. 4 the U shaped metal piece "l" is provided with two upwardly projecting ears "m" in which 105 is pivoted a tongue member "n" having a

downwardly projecting serrated or toothed edge "o". The overlapping portion "d" of the conveyer belt is inserted in the fasteners while the tongue "n" is swung upward. The tongue "n" is then pressed down causing the teeth to engage the conveyer belt cloth and holding it securely in position.

It will be apparent from the foregoing description that by the use of my readily 10 adjustable fastener much time will be saved, and the belt held together with greater security than has been possible under the old system of tying with strings. No damage 15 is done to the belt while under the old method the belt was often torn or otherwise damaged.

Having thus described my invention, what I claim as new and desire to secure by Letters Patent, is—

20 1. A detachable spring metal conveyer belt fastener adapted to hold together two overlapping pieces of belting along their aligned edges, said fastener having a U-shaped portion adapted to frictionally engage one of said overlapping pieces and clamping means secured to said U-shaped portion constructed and arranged to cooperate with said U-shaped portion to engage the other piece.

2. A detachable spring metal fastener 30 adapted to hold together two overlapping pieces of thin flexible material along their aligned edges, having a U-shaped portion adapted to frictionally engage one of said overlapping pieces and a projecting spring 35 tongue spaced from and overlying said U-shaped portion constructed and arranged to frictionally engage and clamp the other of said overlapping pieces against said U-shaped portion of the fastener.

3. A detachable spring metal fastener 40 adapted to hold together two overlapping pieces of thin flexible material along their aligned edges, having a U-shaped portion adapted to frictionally engage one of said overlapping pieces, and a projecting spring 45 tongue spaced from and overlying said U-shaped portion constructed and arranged to engage the other of said overlapping pieces, a projection extending from said U-shaped portion into the space between said portion and said tongue, said projection adapted to engage a suitable eyelet in said other overlapping piece.

Signed at New York in the county of 55 New York and State of New York this 28 day of January A. D. 1922.

HUGO CLAUSSEN.
